UNITED STATES PATENT OFFICE.

ALBERT E. HATCH, OF WAKONDA, SOUTH DAKOTA.

GAME APPARATUS.

Application filed June 2, 1921. Serial No. 474,474.

To all whom it may concern:

Be it known that I, ALBERT E. HATCH, a citizen of the United States, residing at Wakonda, in the county of Clay and State 5 of South Dakota, have invented certain new and useful Improvements in Game Apparatus, of which the following is a specification.

This invention relates to improvements in game apparatus for playing base ball.

10 The primary object of the invention is the provision of an amusing game device, simulating a base ball field, and including mechanical, pitching, batting, and catching means of variable actions, adapted for operation by two or more persons.

15 A further object of the improved game apparatus is the provision of a playing board simulating a base ball field, and including various hazards for testing the skill of persons playing the game.

20 Other objects and advantages will be apparent during the course of the following detailed description.

25 In the accompanying drawings, forming a part of this specification, and in which similar reference characters designate corresponding parts throughout the several views:

30 Figure 1 is a plan view of the improved game apparatus.

Fig. 2 is a cross sectional view of the improved game apparatus taken on the line 2—2 of Figure 1.

35 Fig. 3 is a fragmentary enlarged plan view of the mechanical batting apparatus.

Fig. 4 is a fragmentary cross sectional view of the batting apparatus illustrated in Figure 3.

40 Fig. 5 is a fragmentary plan view of the improved mechanical pitching apparatus.

Fig. 6 is a fragmentary side elevation of the improved pitching apparatus illustrated in Figure 5.

45 In the drawings, wherein for the purpose of illustration is shown the preferred embodiment of my invention, the letter A designates a field, or playing board having the base ball field thereon. A mechanical pitching device B is provided for projecting a ball element C, as in the ordinary ball game, towards a mechanical batting apparatus D. A mechanical catching arrangement E is provided for receiving balls C directly from the pitching means B.

55 The game board A, can of course be of any approved dimensions, thirty inches by

thirty-six inches preferably making a desirable playing field. The supporting table 10 of the game board A may be of any approved material, and preferably supported by vertical sides 11, having portions 12 projecting upwardly therefrom, and portion 13 depending therefrom, to support the table element 10 intermediate the top and bottom edges of the sides 11. Supporting ledges 14 are provided in fixed manner to the sides 11, and for directly supporting the table 10, although this arrangement need not be strictly adhered to. A support 15, is provided centrally of the board 10, and extending longitudinally thereof, for affixing to opposite sides 11, and for purpose of receiving portions of the pitching and batting arrangements B and D respectively, to be subsequently described. It is preferred that the table 10, be divided by fine wires 16, in such manner as to provide a base ball diamond 17, of relatively small size, although proportioned according to standard base ball diamond dimensions. The outfield upon the playing board 10, is further sub-divided by the wires 16, into succeeding zones 18, 19 and 20. Thus, the space within the diamond 17, is conveniently known as the first base zone; next succeeding zone 18 as the second base zone; the next succeeding zone 19, as the third base zone; and the last zone 20, as the home run zone. In the arrangement of the wires 16 upon the table 10, the same are affixed in any approved manner to project upwardly from the plane as defined by the top surface of the table 10, thus providing a hazard, normally maintaining the ball element C in its closest zone, depending upon speed of the ball C as the same rolls over the table 10.

85 Pockets 21, 22, 23 and 24, are preferably positioned in zone 18, adjacent zone 17, said pockets respectively designating first baseman, second baseman, short stop and third baseman. Similar pockets 25, 26, 27, and 28, are preferably positioned in the third base zone 19, the same designating respectively the right fielder, right center fielder, left center fielder, and left fielder respectively. The pockets 21 to 28 inclusive, are preferably of relatively large size, and formed of foraminous material such as netting, and staggered in appropriate manner, to render it difficult for ball C to travel into the home run zone 20. The diamond 17, is preferably provided in a conventional manner with a

home run plate 29. Suitable apertures 30, are provided downwardly in the table 10, in conventional manner in the corners of diamond 17, to designate first, second, and 5 third bases. They are provided for detachable reception of pins 31, said pins being hereinafter referred to as base runners. When not in use, the pins 31 are conveniently positioned in apertures upon the 10 table 10, outside of the base ball field playing zones.

The pitching apparatus B, is placed in conventional manner in the center of diamond 17. Guide arms 35 and 36, are provided as part of the pitching apparatus B, and each include a portion 37, adapted for lying flat upon the top of table 10, for detachable assemblage thereto as by screws 38. A flexible and resilient forward portion 39 20 is provided upon each of the arms 35 and 36, extending in a plane at right angles to the plane of portion 37. The arms 35 and 36 are positioned in such manner that the resilient portions 39 thereof project toward the home 25 plate 29, and are spaced a sufficient distance to provide a guide way for the ball C. A ball engaging element 40, is detachably and oscillatably pivoted at 41 to a side of the longitudinal support 15, as clearly shown in 30 Figure 6 of the drawings. In this arrangement, the free end 42 of the ball engaging element 40, projects upwardly through a slot 43^a in the table 10, and into the guide way provided by the arms 35 and 36.

35 A resilient spring element 43, preferably an elastic band, is affixed at one end to a detachable eye 44, engaging the longitudinal support 15. The opposite end of the spring element 43, is provided to engage about the ball engaging element 40, to maintain the same in tension to propel the ball C. The spring element 43, is, moreover, slideable upon the element 40, and can be adjusted upon said element 40, at any convenient position intermediate the pivot 41, and the free end 42, to provide variable tensioning, to be hereinafter mentioned. A pawl disc 45, is 40 preferably pivoted at 46, within a recess 47 in the longitudinal support 15; said pawl 45 having a tooth 48 upon a corner thereof adapted for engagement about the ball engaging element 40, to maintain the same in cocked position, and against tension of the 45 band or spring element 43. An arcuate spring 49, engages the pawl 45, at the ends 50^a, to maintain the same in spring actuated position to engage the pitching member 40. A pawl releasing arm 50, is preferably pivoted to the pawl disc 45, and extending laterally to support a handle engaging knob 51, projecting from a side 11, as is clearly shown in Figure 2 of the drawings.

Thus, the mechanical pitching device B. 60 has been provided, of considerable scope, in

that the same simulates to a great extent the pitching activities of a base ball pitcher. In operation, the ball C is placed between the resilient portions 39 of the arms 35 and 36, directly over the slot 43^a. The member 40, 70 has of course been drawn rearwardly to be held in cocked position by the tooth 48 of the pawl 45, and against tension of the band 43. As the person playing the game, or having control of the team in the field releases 75 the operating or releasing rod 50, by pushing upon the knob 51; the pawl 45, will be rocked in such manner that the tooth 48 disengages the pitching member 40. The spring 43 will of course act, and propel the ball C forwardly between the arms 35 and 36, and toward the home plate 29. Various speeds can be given to the ball C, by merely adjusting the band 43, as hereinbefore mentioned, upon the element 40. 85

Referring to the batting mechanism D, the same preferably includes a body stem 60, rotatably mounted by a pin 61 upon an outwardly extending shelf 62; said shelf 62 being mounted beneath the longitudinal support 15. The stem 60, projects freely through an aperture 63 in the table 10, and upwardly therefrom, to one side of the home plate 29, and assumes the conventional position of a batter with respect to a home plate. The upper projecting end of the body 60, is provided with an outwardly extending bat structure 64, extending at right angles to the axis of the body 60, and horizontally over the table 10, to simulate a bat in the 90 batter's hands. A spring 65, in the present instance, preferably an elastic rubber band, is secured by an eye 66 to the stem 60 adjacent the shelf 62; and at its other end secured through an eye 67; said eye 67 being secured to a side of the longitudinal support 15. In this manner, when it is desired, to use the body 60 as a support for swinging the bat 64, it is merely necessary to rotate the body or stem 60 upon the shelf 62, and the spring element 65 will be wound about the element 60, and tensioned in this manner for swinging the bat 64. 95

A disc plate or pawl 68, is provided in a recess, or cut out portion 69 of the rafter 15, immediately adjacent the element 60, said pawl 68 being pivotally and detachably mounted at one end 70 within this recess 69. A tooth 71 is formed in one corner of the pawl 68, for engagement by a tooth 72 rigidly mounted laterally in the stem 60. A spring 73, is mounted about the pivot 70, and having its ends 74 extending outwardly and engaging certain portions of the disc 68, to normally force the tooth 71 into engagement with the stem 60, and more particularly the tooth 72. A release rod 75, is pivotally mounted to the disc pawl 68, intermediate the tooth 71 and the pivot 70; said release rod 75 extending longitudinally and parallel 100 to the axis of the stem 60. 105

lel with the brace 15, and having a knob or hand engaging enlargement 76 thereon adapted to project through a suitable aperture in the side 11, to extend from said side, as clearly shown in Figure 1 of the drawings.

In operation, the player representing the team at the bat, winds up the body stem 60, until the same has been secured at the desired tension, by means of the spring band 65. In this connection, it will be observed that the tooth 72 upon the stem 60 will engage the outer bevelled side of the tooth 71, and rides thereover as the stem 60 is being wound for batting purposes. However, when the person representing the team at bat releases the stem 60, the same is unwound, until the tooth 72 engages the relatively straight side of the tooth 71, and remains in this position, and against the tension of spring band 65. When ready for batting in this tensioned position, the bat element 64, extends directly away from the pitcher arrangement B, and in parallel alignment with the axis of the diamond 17, drawn from home plate 29 to second base 30. As the mechanical pitcher B, hurls the ball C through the air in the above described manner, the person representing the team at the bat, will press inwardly upon the release rod 75, and which will have the effect of disengaging tooth 72 from tooth 71. The spring 65, will of course exert itself, and the stem 60 will be rapidly rotated, swinging the bat 64 around and over home plate 29, to strike at the approaching ball C. This batter element D, likewise, embodies many features found in actual base ball play, namely the ability to swing the bat 64 with varying force.

The catcher arrangement E, is of novel formation, the same preferably comprising a short arm 77, and a relatively longer arm 78. Both of the arms 77 and 78, are attached by a portion 79 in rigid manner to the inside of the upwardly extending portion 12 of the side 11, immediately rearwardly of home plate 29. In this position, a resilient vibratory portion 80 of arm 77 projects over the table 10; while a vibratory relatively longer extension 81 projects forwardly of the attaching portion 79 of arm 78, and having its free end 81 arcuated, and in close proximity to home plate 29. This catcher arrangement E is provided, so that as the ball C is projected toward home plate 29; said ball C will hit the vibratory portion 80 of arm 78, and thus glance off therefrom, into engagement with the vibratory portion 80 of arm 77. The ball C will then be forced from one arm 77 to the opposite arm 78, and vice versa, back and forth, until the ball C comes to rest within the pocket 82 provided by the arms 77 and 78. Attention is called to the fact that the outer free end

of the bat 64, is adapted to contact the vibratory portion 80 of the arm 78 when swinging to strike at an approaching ball. This will set the portion 80 of arm 78 into vibration, and if the player controlling the bat 64 misses the ball, the ball will more readily be assured of retention within the pocket 82. Winding of the stem 60, can of course take place regardless of contact with the bat 64 with the portion 80, due to the arcuate surface 81.

The rules applicable to the game can of course be the ordinary base ball regulations. The game is usually played by two persons, one person controlling the pitching arrangement B; the other person controlling the batting arrangement D. A batted ball, rolling into any of the pockets 21 to 28 inclusive, will put that batter out, and will count one out for the person operating the mechanism D. When three are out, the players change sides, by reversing their control of the pitching and batting mechanisms. The batted ball rolling within the diamond 17, being in the first zone, will entitle the person controlling the mechanism D to a runner 31 on first base. The pins 31, are of course advanced in the pockets 30, as succeeding players hit the ball into any of the above mentioned zones. In the ordinary manner, the game proceeds in accordance with base ball rules. Should a pitched ball hit the post 60, when the person operating the mechanism D did not release the bat 64 for swinging, said player operating D is entitled to advance his players one base. Great interest is attached to the game by reason of the variable speed with which the ball C can be hit as indicated by the adjustment of tensioning the spring element 43. In corresponding manner, the batter can swing the bat 64 at various speeds, to knock the ball C into succeeding zones as desired by tensioning of the spring means 65.

Various changes in the shape, size, and arrangement of parts may be made to the form of the invention herein shown and described, without departing from the spirit of the invention or the scope of the claims.

I claim:

1. A game apparatus, comprising in combination a playing support simulating a base ball field, a ball, mechanical means for pitching said ball, mechanical batting means, and catching means mounted to the rear of the abutment means and including vibratory gripping arms extending towards the batting means in spaced relation to each other and adapted to be vibrated towards and away from each other through being struck by the batting means whereby the ball may be buffeted between said arms when caught.

2. A game apparatus, comprising in combination a playing support simulating a base ball field, a ball, mechanical means for pitch-

ing said ball, mechanical batting means, and catching means including vibratory guide arms, said batting means adapted to strike one of said arms when operated, to vibrate the same to facilitate retention of the pitched ball by said catching means.

3. A game apparatus comprising a support constituting a playing field, batting means carried by said support, a ball to be projected towards the batting means and

catching means carried by said support to the rear of the batting means and having spaced ball gripping arms extending towards the batting means with one arm longer than the other and adapted to be struck by the 25 batting means and vibrated to cause buffeting of a ball projected towards the batting means and caught between said arms.

ALBERT E. HATCH.
